(57) **CLAIM**

The ornamental design for a display screen or portion thereof with graphical user interface, as shown and described.

DESCRIPTION

FIG. 1 is a front view of a display screen or portion thereof with graphical user interface of a first embodiment showing the claimed design;

FIG. 2 is a front view of a display screen or portion thereof with graphical user interface of a second embodiment showing the claimed design;

FIG. 3 is a front view of a display screen or portion thereof with graphical user interface of a third embodiment showing the claimed design;

FIG. 4 is a front view of a display screen or portion thereof with graphical user interface of a fourth embodiment showing the claimed design;

FIG. 5 is a front view of a display screen or portion thereof with graphical user interface of a fifth embodiment showing the claimed design;

FIG. 6 is a front view of a display screen or portion thereof with graphical user interface of a sixth embodiment showing the claimed design;

FIG. 7 is a front view of a display screen or portion thereof with graphical user interface of a seventh embodiment showing the claimed design;

FIG. 8 is a front view of a display screen or portion thereof with graphical user interface of an eighth embodiment showing the claimed design;

FIG. 9 is a front view of a display screen or portion thereof with graphical user interface of a ninth embodiment showing the claimed design;

FIG. 10 is a front view of a display screen or portion thereof with graphical user interface of a tenth embodiment showing the claimed design;

FIG. 11 is a front view of a display screen or portion thereof with graphical user interface of an eleventh embodiment showing the claimed design;

(Continued)

FIG. 12 is a front view of a display screen or portion thereof with graphical user interface of a twelfth embodiment showing the claimed design;

FIG. 13 is a front view of a display screen or portion thereof with graphical user interface of a thirteenth embodiment showing the claimed design;

FIG. 14 is a front view of a display screen or portion thereof with graphical user interface of a fourteenth embodiment showing the claimed design; and,

FIG. 15 is a front view of a display screen or portion thereof with graphical user interface of a fifteenth embodiment showing the claimed design.

The broken lines, texts, and numerals in the figures show portions of the graphical user interface that form no part of the claimed design.

The outmost dot-dashed lines in the figures show a display screen or portion thereof, and form no part of the claimed design.

1 Claim, 15 Drawing Sheets
